UNITED STATES PATENT OFFICE.

WILLIAM REUSCH, HENRY ALTHEIDE, AND PAUL R. REUSCH, OF ANAHEIM,
CALIFORNIA.

DUSTLESS AUTOMOBILE BREATHER.

Application filed October 11, 1921. Serial No. 507,139.

To all whom it may concern:

Be it known that we, WILLIAM REUSCH, HENRY ALTHEIDE, and PAUL R. REUSCH, citizens of the United States, residing at 5 Anaheim, in the county of Orange and State of California, have invented certain new and useful Improvements in Dustless Automobile Breathers; and we do hereby declare that the following is a full, clear, and concise description of the same, such as will 10 enable others skilled in the art to which it appertains to make and use the same.

This invention has reference to improvements in engine attachments, having for an 15 object to provide a novel form of breather device for use in connection with the crank cases of engines, such as are usually employed for propelling vehicles, whereby the air drawn into the engine crank case will 20 be thoroughly filtered and freed of dirt, dust, sand, and other foreign matter, which when admitted to the crank case will mix with the lubricating oil circulating therein and because of its abrasive action upon the various 25 bearing surfaces therein effect premature deterioration of the same.

Among other objects of the invention may be recited, the provision of a device of the character mentioned with a view towards 30 compactness, and in which the number of parts is few, the construction simple, the cost of production small and further, a device which may be attached to practically all forms of prevalent types of engines with 35 but slight alteration thereto.

Other objects will be in part obvious and in part pointed out hereinafter.

In order that the invention and its mode of operation may be readily understood by 40 persons skilled in the art, we have in the accompanying illustrative drawings and in the detailed following description based thereon set out one possible embodiment of the same.

45 In these drawings:—

Figure 1 is a side elevation of the improved breather device applied to a fragment of an engine crank case;

Figure 2 is a vertical section through the 50 same;

Figure 3 is a horizontal section therethrough taken on the line 3—3 of Figure 2 looking in the direction in which the arrows point; and,

Figure 4 is a detail in perspective of the 55 filter.

Having more specific reference to the drawings, in connection with which like characters of reference will designate corresponding parts throughout, we have shown 60 our improved breather device as applied to the crank case of an engine, fragmentally shown and indicated by the numeral 1, said crank case having an opening formed therein adapted to receive the usual breather. 65

Our improved breather comprises a housing divided into juxtaposed chambers 2 and 3, the upper ends of which are opened and internally screw threaded whereby to engage correspondingly screw threaded caps 70 4 and 5. In this connection, it is to be noted that the communication as between the juxtaposed chambers 2 and 3 of the breather device is established by way of a port 6 formed in the intermediate wall of the chambers, and 75 because of the fact that a plurality of orifices or ports 7 are formed in the lower end of the chamber 3, which as will be noted, is of less size than the chamber 2, air will be permitted to be drawn into said chamber 80 3 and from there through the port 6 into the chamber 2 for discharge into the crank case 1 by way of the reduced open lower end 8 of the chamber 2 which lower end, as will be noted, is of a size such as will insure its 85 snug reception in the opening formed in the crank case; the annular shoulder formed by said reduction resting upon the adjacent portion of said crank case.

In order that the breather device housing 90 may be securely connected to the crank case 1 and held thereupon against any undue movement or vibration, a spider 9 is arranged within the chamber 2, preferably intermediate its upper and lower ends and receives through a central opening formed therein the upper screw threaded portion of a connecting or tie rod 10, the lower end of the rod being hooked as at 11 and adapted to engage with a transversely disposed anchoring bar 12 which is arranged in the crank case 1 and has its opposite ends engaging adjacent portions of said case. Thus, with engagement of the nut 13 with that portion of the connecting rod 10 extending above 100 the spider 9, the hook 11 will be engaged with the anchoring bar 12 and upon tightening of the locking screw 13 will effect the 105

clamping of the breather device housing in position upon the crank case 1, with the necessary degree of rigidity.

Removably positioned in the chamber 6 is a perforate cylindrical shell 14 having the upper end thereof reduced and formed with an opening 15 through which horse hair or other suitable filtering matter 16 may be introduced into said shell as clearly shown in the Figure 2. In this connection, it is to be noted that the cross sectional shape and size of the perforate shell 14 is such as will permit of its snug reception in the chamber 3 and by consequence, with arrangement of the filtering means over the orifices 7, such air as passes therethrough into the chamber 3 and through the port 6 in the chamber 2 for passage into the crank case 1 will be thoroughly filtered, since it must necessarily pass through the filtering matter 16. Therefore, it is to be understood that the air delivered into the crank case 1 by way of our improved breather device will be thoroughly filtered and thus, relieved of dirt, dust or sand or the various other foreign matters which upon mixing with the oil to any material extent will cause the same to have detrimental effect upon the bearing surfaces coated thereby.

In using our improved breather device, oil may be readily introduced into the crank case 1 by merely removing the closure cap 4 from the upper screw threaded extremity of the casing. When it is needed the filtering means contained in the perforate shell 14 may be replenished by removing the same through the upper end of the chamber 3, the closure cap 5, of course, having been previously disengaged from its screw threaded upper end. If necessary it may be entirely removed and renewed.

Manifestly, the construction shown is capable of considerable modification and such modification as is within the scope of

our claims, we consider within the spirit of 45 our invention.

We claim:

1. A breather pipe comprising a pair of substantially cylindrical chambers communicating with each other near their upper ends, removable closure members for the upper ends of said chambers, the lower ends of said chambers being provided one with an air inlet opening and the other with an air outlet opening, and filtering means removably mounted in one of said chambers.

2. A breather pipe comprising a pair of substantially cylindrical chambers communicating with each other near their upper ends, removable closure members for the upper ends of said chambers, the lower ends of said chambers being provided one with an inlet opening and the other with an air outlet opening, a perforated shell removably arranged in one of said chambers, and filtering material arranged in said shell.

3. A breather pipe comprising a pair of substantially cylindrical chambers communicating with each other near their upper ends, removable closure members for the upper ends of said chambers, the lower ends of said chambers being provided one with an inlet opening and the other with an air outlet opening, a perforated shell removably arranged in one of said chambers, filtering material arranged in said shell, a rod mounted in the other of said chambers, said rod projecting through said outlet opening, and having a hook formed on its end, and a transverse member arranged in the crank case, and adapted to be engaged by said rod to retain the device in position.

In witness whereof we have hereunto set our hands.

WILLIAM REUSCH.
HENRY ALTHEIDE.
PAUL R. REUSCH.
